DISPLAY RACK FOR MAGAZINES, FOLDERS, AND THE LIKE

Filed July 5, 1929

Fig. 1.

UNITED STATES PATENT OFFICE

WILLIAM C. KELLEY, OF DES MOINES, IOWA

DISPLAY RACK FOR MAGAZINES, FOLDERS, AND THE LIKE

Application filed July 5, 1929. Serial No. 376,062.

The object of this invention is to provide an improved construction for a display rack for magazines, folders, and other merchandise by means of which such merchandise may be easily and conveniently displayed.

A further object is to provide an improved display rack having adjustable partitions capable of forming compartments of various widths.

Still another object is to provide an improved means for mounting adjustable partitions in a display rack of the character described.

Another and further object is to provide an improved construction for a slidable partition for a display rack which is so arranged as to form lateral supports for the merchandise and also is provided with efficient means for holding the partition in proper position.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of a display rack constructed in accordance with my invention.

Figure 2 is a side elevation of the same.

Figure 3 is a vertical section through a portion of the rack on the line 3—3 of Figure 1.

Figure 4 is a horizontal section on the line 4—4 of Figure 2, illustrating particularly the method of employing two adjustable partitions for forming a compartment and a supporting means for the merchandise.

Figure 5 is a perspective view showing one of the adjustable partitions removed from the rack.

In carrying out my invention I employ one or more display units which may, if desired, be assembled in the form of a structure such as is shown in Figures 1 and 2. This structure as here shown includes a base frame 10 and end walls 11 and 12 rising therefrom. The front wall of the structure may be composed of a plurality of display units, in this instance

four in number and designated generally as A, B, C and D.

The display units in the structure may be of various sizes, particularly as to height or vertical width and preferably are arranged in stepped relation, whereby each unit is in a plane slightly rearwardly of the adjacent lower unit. Each of the display units includes a panel or rear wall 13 formed of sheet metal and bent substantially at right angles at its lower margin to produce a bottom wall 14.

The bottom wall is bent or turned upwardly at its forward margin to produce a front flange 15, which is of considerably less height than the rear wall 13. Between the bottom wall 14 and front flange 15 the metal is bent and shaped to produce a slide bearing 16, which is in a plane just above the bottom wall and preferably projects somewhat forwardly of the front flange 15, as clearly shown in Figure 3.

Extending longitudinally of the rear wall 13 and spaced materially above the bottom wall 14 is a downwardly opening slide bearing designated by the numeral 17. The slide bearing 17 may be formed of a separate strip of metal suitably attached to the face of the rear wall 13.

With each of the display units I employ a number of slidable or adjustable partition members E, one of which is shown in Figure 5. Each partition member E may be formed of two pieces of metal which are bent and shaped in a similar manner, but with parts oppositely arranged so that they may be secured together by suitable means such as spot welding to produce a member which is substantially H-shaped in cross section.

Each partition member includes a web portion 18, which is vertically arranged in a plane transversely of the display unit and is formed at its forward margin with right angled flanges 19 and 20 extending in opposite directions from the plane of the web. At its rear margin the web 18 is formed with oppositely directed vertical flanges 21 and 22, which are parallel with the flanges 19 and 20 and the flanges 21 and 22 project upwardly

above the upper margins of the web and front flanges to produce lips 23.

At its lower margin, the twin portions of the web 18 are bent outwardly in horizontal planes to form base flanges or feet 24 and 25 of considerable extent and said base flanges project forwardly of the vertical plane of the front flanges 19 and 20 to produce lips 26.

The partition members E are capable of being removably and adjustably mounted in either of the display units and when so mounted, the base flanges 24 and 25 rest on the bottom wall 14 of the display unit with the lips 26 thereof engaging in the forward slide bearing 16. The lower portions of the front flanges 19 and 20 contact with the front flange 15 of the display unit. The rear flanges 21 and 22 contact with the rear wall 13 of the display unit and the lips 23 of said flanges are received within the upper slide bearing 17.

When so mounted, the partition members form sliding separating means and supporting means for merchandise such as magazines, folders, boxes, cartons or the like, indicated at 27.

The partition members are initially mounted in the display units by endwise movement, whereby the lips 26 and 23 are caused to engage in the slide bearings 16 and 17 respectively and they may be adjusted as to spacing in such manner as to accommodate merchandise packages 27 of varying widths, as clearly illustrated in Figure 1.

The packages 27 rest at their lower margins on the bottom walls 14 and on the base flanges 24 and 25 and are supported against outward or forward movement by the front flanges 19 and 20 of the partition members.

The partition members may be so constructed that they fit quite snugly in the display units and in the slide bearings thereof so that they tend to remain in any position in which they may be placed and yet are capable of manual adjustment longitudinally of the display units, as desired.

The partition members E for a given display rack may be alike in size and shape and the different display units such as A, B, C and D, may be uniform in width and in spacing of their upper slide bearings 17 above their bottom walls. By this arrangement, the partition members E may be transferred from one unit to another if desired and yet, the lower display units may be made of greater height above the slide bearings 17 so as to accommodate merchandise packages of greater height in the lower units and of less height in the upper units.

In the accompanying drawings, I have shown the display units as mounted in substantially vertical positions and in the description, I have for convenience, referred to the walls 13 as rear walls and the walls 14 as bottom walls.

It is to be understood, however, that the units may be mounted in any desired positions of inclination and that other modifications and alterations may be employed within the scope of the appended claims without departing from the spirit and purpose of my invention.

I claim as my invention:

1. A display device comprising a panel having a back wall and a bottom wall, a slide bearing formed adjacent the forward part of said bottom wall, a slide bearing on said back wall, and a series of movable partition members cooperating with said panel, each partition member having parts receivable in each of said slide bearings, each partition member also having relatively broad base flanges resting on said bottom wall.

2. A display device comprising a panel having a back wall, a low front wall and a bottom wall, a slide bearing formed at the forward part of said bottom wall, a slide bearing on said back wall, a series of movable partition members cooperating with said panel, each partition member having parts receivable in each of said slide bearings, and also having oppositely extending flanges at its forward margin for engaging and holding an object between adjacent partition members, said flanges extending above the low front wall for holding and displaying objects between adjacent partition members.

3. A display device comprising a panel having a back wall and a bottom wall, a slide bearing formed at the forward part of said bottom wall, a downwardly opening slide bearing on said back wall, and a series of movable partition members cooperating with said panel, each partition member having parts receivable in each of said slide bearings, each partition member also having relatively broad base flanges resting on said bottom wall and serving to prevent tipping of the partition member.

4. A display device comprising a panel having a back wall and a bottom wall, a slide bearing formed at the forward part of said bottom wall, a downwardly opening slide bearing on said back wall, a series of movable partition members cooperating with said panel, each partition member having parts receivable in each of said slide bearings, and also having oppositely extending flanges at its forward margin for engaging and holding an object between adjacent partition members, each partition member also having relatively broad base flanges resting on said bottom wall and serving to prevent tipping of the partition member.

5. A display device comprising a panel having a back wall and a bottom wall, a slide bearing formed at the forward part of said bottom wall, a downwardly opening slide bearing on said back wall, and a series of movable partition members cooperating with

said panel, each partition member having a forwardly directed lip engageable in the forward slide bearing and an upwardly directed lip engageable in the upper slide bearing.

6. In a display device, an elongated compartment having a longitudinal slide bearing at its lower front portion and a longitudinal slide bearing on its rear wall, and a series of 10 adjustable partition members each having a web portion arranged transversely of the compartment, each partition member having a lip receivable in each of said slide bearings and also having lateral flanges at the forward 15 margin of its web portion and extending substantially throughout the vertical dimension of the partition member for engaging and holding objects between adjacent partition members.

20 7. In a display device having an elongated chamber formed with a downwardly opening slide bearing on its rear wall and a rearwardly opening slide bearing in the forward portion of its base, a movable partition member 25 comprising a web portion adapted to extend transversely of the chamber, oppositely directed flanges at the forward margin of said web, to form holding means for objects located between partition members, 30 base flanges at the lower ends of said web, and means on said partition member for slidably engaging each of said slide bearings.

35 8. In a display device having an elongated chamber formed with a downwardly opening slide bearing on its rear wall and a rearwardly opening slide bearing in the forward portion of its base, a movable partition member comprising a web portion adapted to extend transversely of the chamber, oppositely directed flanges at the forward margin of said web, to form holding means for objects located between partition members, 40 base flanges at the lower ends of said web, rear flanges at the rear margin of said web, and means on said partition member for 45 slidably engaging each of said slide bearings.

45 9. In a display device having an elongated chamber formed with a downwardly opening slide bearing on its rear wall and a rearwardly opening slide bearing in the forward portion of its base, a movable partition member 50 comprising a web portion adapted to extend transversely of the chamber, oppositely directed flanges at the forward margin of said web, to form holding means for objects located between partition members, base flanges 55 at the lower ends of said web, rear flanges at the rear margin of said web, and lips formed on the upper ends of the rear flanges and on the forward ends of the base flanges for 60 slidably engagement in the respective slide bearings.

Des Moines, Iowa, September 1, 1928.
